UNITED STATES PATENT OFFICE

1,970,692

FLASHING

Charles A. Earley, Dorchester, Mass.

Application September 6, 1932, Serial No. 631,826

4 Claims. (Cl. 72—127)

This invention relates to improvements in sheet metal flashing and has for its object to provide a strip of flashing that may be inserted in the binding material that is employed between the 5 adjacent courses of masonry of a wall for the purpose of arresting the downward seepage of water through said wall, and then diverting said water to the exterior of the wall.

Another object of the invention is to form a 10 strip of flashing in such a manner that when it is inserted in the binding material for the masonry structure the flashing will be prevented from moving in said structure in a horizontal plane. 15 Another object of the invention is to provide the flashing with longitudinally and transversely extending rows of intersecting corrugations between which are also provided both longitudinally and transversely extending intercommunicating grooves, all of which are so arranged that when the flashing is inserted in the binding material of the masonry structure it will be prevented from moving in a horizontal plane therein.

Still another object of the invention is to provide 25 the strip of flashing with a novel form of cap which may be positioned as desired upon the projections or corrugations in a manner to bridge the intervening grooves, making it impossible for the binding material to enter these grooves and 30 thereby providing a drain above the flashing through the binding material to the exterior of the wall.

The invention consists in an improved form of sheet metal flashing and cap therefor as set 35 forth in the following specification and particularly as pointed out in the claims thereof.

Referring to the drawing:

Fig. 1 represents a plan view of a portion of a strip of flashing embodying my invention. 40 Fig. 2 is a detail sectional view of a portion of a wall illustrating the adjacent end portions of two strips of flashing interlocked together and embedded in the binding material that is employed between adjacent courses of masonry, said 45 section being taken through one of the strips as indicated by the line 2—2, Fig. 1, looking in the direction of the arrows on said line.

Fig. 3 is a detail sectional view illustrating adjacent courses of masonry of a wall with the flashing embedded in the binding material therebetween, the section extending through a strip of flashing as indicated by the line 3—3, Fig. 1, looking in the direction of the arrows on said line. 50 Fig. 4 is a plan view of a portion of a strip of

flashing illustrating corrugations or projections of a modified type formed thereon.

Fig. 5 is a detail sectional view through a wall and through the flashing as indicated by the line 5—5 of Fig. 4, looking in the direction of the arrows on said line. 60

Fig. 6 is a detail sectional view through a wall and through the flashing as indicated by the line 6—6 of Fig. 4, looking in the direction of the arrows on said line. 65

Fig. 7 is a detail sectional view illustrating another modified embodiment of the invention.

Like numerals refer to like parts throughout the several views of the drawing. 70

In the drawing, referring particularly to Figs. 1, 2 and 3, 10 represents a strip of flashing preferably constructed of sheet metal. Formed at regular intervals upon the strip of flashing 10 are rows of both longitudinally and transversely extending corrugations 11, between which are longitudinally extending grooves 12 and transversely extending grooves 13, all of which communicate with each other. The rows of corrugations 11 are formed as pyramidal projections 14 which are pressed upwardly from the sheet of flashing 10, thereby forming pyramidal recesses 15 upon the underside of the flashing. The projections 14 and recesses 15 are so formed that when the strip of flashing 10 is inserted in the binding material 16 of a wall 17, which may consist of any suitable form of masonry, the binding material will enter the grooves 12 and 13 that are provided upon the upper surface of the flashing and recesses 15 upon the under surface of the flashing and act to bond the strip of flashing and binding material together and prevent the flashing from moving in a horizontal plane in the binding material and between the courses of masonry. It will be noted that the grooves 12 and 13 and recesses 15 are all formed in such a manner that the binding material 16 will easily enter all parts of said grooves and recesses without it being necessary to apply excessive pressure to either the binding material or the flashing. 85

Positioned at intervals upon the upper surface of the flashing 10 and extending transversely thereacross is a cap 18, which rests upon the tops of two adjacent transversely extending rows of projections 14 and bridges the intervening groove 12, leaving a space therebeneath from which the binding material 16 will be excluded, thereby forming a drain which will extend across the strip of flashing. The opposite longitudinal edge portions 19 of the cap 18 are bent downwardly and engage the sides of the projections 14 in a man- 100

105

110

116

ner to positively position the cap 18 upon the projections. The cap 18 may rest loosely upon the projections 14, or it may be permanently secured thereto by solder, if it is so desired.

5 A cap 20, constructed in the same manner as the cap 18, may extend longitudinally of the strip of flashing 10 between the caps 18 and rest upon adjacent longitudinally extending rows of projections 14 in a manner to provide an open 10 longitudinally extending drain therebeneath, and it is evident that as many of these longitudinally extending caps may be provided as may be desired, and the drains provided therebeneath will communicate with the transversely extending 15 drains.

In Figs. 4, 5 and 6 I have illustrated a modified embodiment of my invention in which a strip of flashing 21 is provided with rows of longitudinally and transversely extending corrugations 22 20 formed approximately as pyramidal projections 23, between which are located longitudinally and transversely extending grooves or depressions 24 which communicate one with another.

In this form of flashing the obverse and reverse 25 surfaces of the flashing are identical, and binding material 25 located between courses of masonry of a wall 26 will enter the grooves or depressions 24 and effectively prevent the flashing from moving in a horizontal plane between the 30 courses of masonry. In this form of flashing it will be noted that the projections and depressions are all so formed that the binding material will easily enter all parts of the depressions without it being necessary to apply excessive pressure to 35 either the binding material or the flashing.

Caps, similar to the caps 18 and 20 previously described, may be used if it is so desired in connection with this form of flashing, but it is evident that it will be impossible to entirely drain 40 the upper surface of the flashing, for the reason that the grooves or depressions 24 are not of uniform depth.

In Fig. 7 I have illustrated still another modified embodiment of the invention, in which a strip of flashing 27 is provided with rows of both 45 longitudinally and transversely extending corrugations 28 which are formed as segmental spherical projections 29 which are pressed upwardly from the sheet of flashing, thereby forming recesses 30 upon the under side of the flashing. The projections 29 are spaced at exactly the 50 same manner as are the projections 14 previously described and have longitudinally and transversely extending intercommunicating grooves 55 31 provided therebetween.

A cap 32 similar to the cap 18 previously de-

scribed rests upon the tops of two adjacent transversely extending rows of projections 29 and bridges the intervening groove 31, leaving a space therebeneath from which binding material 33 of a wall 34 will be excluded, thereby forming a 80 drain which will extend across the strip of flashing. Another cap 35, similar to the cap 20 previously described, is also provided, said cap 35 being positioned upon the flashing in exactly the 85 same manner and for the same purpose as is the cap 20.

The flashing illustrated in Fig. 7 is used in exactly the same manner as is the flashing illustrated in Figs. 1 to 3 inclusive, but differs therefrom solely in the fact that the projections 90 are formed as segments of spheres instead of being pyramidal.

I claim:

1. A sheet metal flashing for masonry structures comprising a metal plate having longitudinally and transversely extending rows of intersecting corrugations and intervening intercommunicating grooves adapted to serve as a key for mortar, and a cap embodying therein marginal positioning means, said cap resting upon 100 certain of said corrugations and bridging the intervening grooves.

2. A sheet metal flashing for masonry structures comprising a sheet of metal of the width to extend substantially through the wall of a 105 structure, said flashing being provided with hollow pyramidal projections and intercommunicating arcuate grooves whereby moisture of infiltration from said wall, collecting upon the upper surface of said flashing, may be deflected 110 and drained to an outer surface of said wall.

3. A sheet metal flashing for masonry structures comprising a sheet of metal of the width to extend substantially through the wall of a structure, said flashing being provided with intercommunicating grooves whereby moisture of infiltration from said wall, collecting upon the upper surface of said flashing may be deflected and drained to an outer surface of said wall, and a plurality of intersecting caps resting upon said 120 flashing above certain of said grooves and forming covered intercommunicating drains thereof.

4. A sheet metal flashing for masonry structures comprising a metal plate having raised hollow projections on the surface thereof and a metal cap resting upon certain of said projections and spanning the area of plate therebetween, whereby a hollow space is provided beneath said cap to drain moisture of infiltration to the exterior of said structure.

CHARLES A. EARLEY.
